UNITED STATES PATENT OFFICE

166,433

COMBINED BELT AND HOLSTERS SET

Herman R. Weitzman, Los Angeles, Calif.

Application November 28, 1949, Serial No. 6,301

Term of patent 7 years

(Cl. D34—15)

To all whom it may concern:

Be it known that I, Herman R. Weitzman, a citizen of the United States, residing in the city and county of Los Angeles and State of California, have invented a new, original, and ornamental Design for a Combined Belt and Holsters Set, of which the following is a specification, reference being had to the accompanying drawing, forming part thereof.

Fig. 1 is a front view of a combined belt and holsters set, showing my new design.

Fig. 2 is a rear view thereof.

I claim:

The ornamental design for a combined belt and holsters set, substantially as shown.

HERMAN R. WEITZMAN.
